(57) CLAIM

The ornamental design for a camera carrying case, as shown and described.

DESCRIPTION

FIG. 1 is a front perspective view of a camera carrying case showing my new design, the broken lines depicting environment and forming no part of the claimed design;
FIG. 2 is a front elevation view of the invention illustrated in FIG. 1;

FIG. 3 is a rear elevation view of the invention illustrated in FIG. 1;

FIG. 4 is a right elevation view of the invention illustrated in FIG. 1;

FIG. 5 is left elevation view of the invention illustrated in FIG. 1;

FIG. 6 is a top plan view of the invention illustrated in FIG. 1; and,

FIG. 7 is a bottom plan view of the invention illustrated in FIG. 1.

Throughout the views, the broken lines shown on the surface of the design, are understood to represent stitching.
